ATTACHMENT FOR KNITTING MACHINES

Frank G. Weisbecker, Glenside, Pa., assignor to
Arcadia Hosiery Company, Lansdale, Pa., a cor-
poration of Pennsylvania

Application February 23, 1934, Serial No. 712,618

12 Claims. (Cl. 66—127)

This invention relates to an improvement in knitting machines, and more particularly to an improved device for operating the thread carrier bars in their usual path of movement in a machine of this kind.

In flat knitting machines now generally used, such for example as those used for producing full fashioned hosiery and other similar knitted articles, the thread carriers are mounted upon and move with bars that are commonly called thread carrier bars. These bars may extend for the full length of the knitting machine which is composed of one and up to thirty sections or more. The thread carrier bars are reciprocated longitudinally of the machine, and the limit of their movement is controlled by fixed stops arranged on the knitting machine.

Heretofore, the thread carrier bars have been individually driven by a number of so-called friction boxes (one for each carrier bar) distributed along a friction box rod which extends parallel with the thread carrier bars and is connected to be reciprocated by the well known Coulier drive of the knitting machine. Whenever the character of the knitting operation is changed by adding or changing threads, the friction boxes must be individually adjusted to terminate or initiate the movement of the corresponding carrier bars. In the past, the change-over has been made by the operator manipulating a control lever mounted on each friction box, or, in some machines by automatic regulation of the friction boxes.

These prior known devices have certain disadvantages which the present invention seeks to overcome. As the prior friction boxes were spaced apart, and may extend for a considerable distance along the machine, the manual control operations consumed appreciable time during which the knitting machine must be stopped to permit of changing adjustments. The automatic means involves complicated and expensive mechanisms.

It is, therefore, the principal object of this invention to simplify the drive for the thread carrier bars.

Another object of this invention is to provide a single device capable of simultaneously driving any or all of the carrier bars so that each carrier bar may have independent movement.

It is also an object of this invention to provide means for driving the carrier bars which may be manually controlled and will permit a substantial reduction in time that the knitting machine is idle, while the carrier bars are being

picked up or dropped by the respective driving means. In fact, an alert operator skilled in the use of this invention may make all the necessary adjustments in the drive for the carrier bars when threads are being changed or added, without actually stopping the knitting machine. In practice, it has been found that by the use of this invention the production of full fashioned hosiery per machine has been substantially increased.

Still another object of this invention is to provide a simple drive for the thread carrier bars which permits the use of a simplified automatic control.

A further object of this invention is to provide a drive for thread carrier bars having means capable of adjustment for simultaneously changing the maximum movement of all the thread carrier bars.

Another aim of this invention is to secure the foregoing objects in a control mechanism having the form of an attachment capable of being readily applied to the standard type of flat knitting machines without entailing any material changes either in their construction or normal mode of operation.

Still other objects and attendant advantages of this invention will be manifest from the detailed description following.

In the attached drawing, which discloses a preferred embodiment of this invention,

Figure 1 is a perspective view of the attachment embodying this invention and operatively positioned with relation to the thread carrier bars of a knitting machine;

Figure 2 is an elevational view partly in cross section, of the attachment shown in Figure 1;

Figure 3 is a detailed cross sectional view taken on line III—III of Figure 2.

Referring to the drawing, the attachment is shown applied to a conventional flat knitting machine having the usual carrier bars 1, thread carriers 2, supporting brackets and guides 3 for the carrier bars, and an adjustable carrier bar stop device 4, the specific details of which form no part of this invention.

The attachment or device referred to generally by the reference numeral 5 comprises a drum 6 having an axial extension 7. The drum is suitably secured to a shaft 8 by means of a key 9 and set screw 10. Bearings 11 and 12 support the drum for its intended oscillatory movement. The front bearing 11 receives one end of shaft 8, and rear bearing 12 receives the drum extension 7. The bearings 11 and 12 are mounted upon fixed 110

supporting rods 13 and 14, at front and rear of machine respectively. These rods 13 and 14 constitute no part of the invention, and may be any fixed parts of the machine which will conveniently support this attachment. For purposes of illustration, part of bearing 11 and rod 13 are not shown in Figure 1.

As will be seen from the drawing, the left end of shaft 8 extends beyond the rear bearing 12, and has secured to it a crank arm 15. Key 16 and set screw 17 secure the crank arm 15 to the shaft 8. The crank arm 15 carries a slide 18 which may be adjusted along the length of the crank arm and held in the adjusted position by means of set screw 19. A link 20 is pivotally secured to slide 18 and sleeve 21 by means of pins 22. The sleeve 21 is fixed to and moves with a reciprocating rod 23 which may conveniently be driven from the usual Coulier drive. Rod 23, however, may be any driving element on the machine which will give the desired oscillatory movement to crank arm 15 though means such as link 20.

It is to be understood that crank arm 15 is shown in an upstanding position for purposes of convenient illustration, and that this arm may assume other driving positions about its axis, that driving position being chosen which will be most convenient for coupling the arm to a moving element of the machine, such as reciprocating rod 23.

Drum 6 is held against axial movement in the bearings by means of collars 24 and 25, secured respectively to shaft 8 and drum extension 7.

35 A plurality of channels 26 comprising annular surfaces 27 and annular ribs 28 are formed in drum 6, and each channel may receive a friction unit or band indicated in general by reference numeral 29. In general, there are as many friction units 29 as carrier bars, although it will be understood a less number of friction units may be provided if it is so desired. Each friction unit is designed to operate a separate carrier bar 1.

45 As the friction units are identical in construction, operate in the same way, and are similarly controlled, a detailed description of the construction, operation, and control of one friction unit will be sufficient for an understanding of this invention.

50 Each friction unit 29 comprises a split band 30 of metal, or other suitable material, having a lining 31 of leather, or other suitable material, secured to its inner circumference. An ear 32, on the band 30, a link 33, and a plate 34 mounted on the carrier bar serve as the driving connection between the friction unit and its carrier bar.

55 The means for controlling each friction unit 29 comprises upstanding lugs 35, 36 formed on adjacent ends of the band 30, a strap or link 37 extending across the outer face of lug 35 and along both sides of lugs 35 and 36, and a cam lever 38 pivotally supported by strap 37 so that its cam face 39 may have engagement with outer face 40 of lug 36. A set screw 41 extending through strap 37 and bearing on the lug 35 provides means for adjusting the degree of frictional engagement between the friction unit and drum 6 when cam lever 38 is moved clockwise (Figure 3) to draw lugs 35 and 36 together and cause the friction band to grip the annular surface 27 of drum 6.

60 In the operation of the attachment shown in the drawing, the reciprocating bar 23 through link 20 and crank arm 15 oscillates the drum 6.

75 If it is desired that all carrier bars 1 remain at

rest, the cam lever 38 on each friction unit 29 will be moved to the position shown in Figure 3. In this position of adjustment, the friction members will hang loosely on drum 6 (see Figures 2 and 3) and will not move therewith, as the inertia and resistance to movement of the carrier bars will be sufficient to resist any tendency of the friction units 29 to oscillate with the drum. When it is desired to operate any one of the carrier bars 1, the cam lever 38 of the friction member adapted to drive that particular carrier bar is moved clockwise (as viewed in Figure 3). This movement of the cam lever will cause the friction member 29-31 to contract, and frictionally grip the drum 6 so that they will oscillate together. The carrier bar being driven will then move longitudinally in the direction of the drive until stopped by the usual end stop (not shown). The carrier bar will then halt further movement of the friction unit and the latter will slip on the drum while the latter continues its oscillatory movement in the same direction. When the drum reverses its movement, however, it will pick up the contracted friction member and the corresponding carrier bar, and the latter will be carried along in the opposite direction until it engages another end stop (not shown).

80 Each friction unit or band 29 may be readily controlled by means of its cam lever 38 at any time during the operation of the knitting machine to terminate or initiate the drive of the particular carrier bar with which it is associated.

85 By adjusting slide 18 along the crank arm 15, the amplitude of movement of the arm, and hence the extent of movement of the carrier bars, may be changed as desired. If the slide be moved towards the outer end of the arm, the amplitude of angular movement of the drum, as well as of the arm, is decreased, and each friction member will impart less or shorter movement to its carrier bar. If the slide be moved inwardly, the angular movement (oscillation) of the drum will be increased, and the maximum throw of each carrier bar will be correspondingly increased.

90 It will be understood that this attachment may be used on leggers, footers, and flat knitting machines, and is adapted for use on machines for straight knitting, plating and/or split work. Other uses of this invention will be apparent from the foregoing description and accompanying drawing.

95 While one embodiment of this invention has been shown and described, other forms and modifications embodying the invention may be readily devised within the spirit and scope of the invention, as defined in the following claims.

I claim:

1. In a knitting machine having a driving element and a plurality of thread carriers and carrier bars, an attachment for reciprocating the said bars to thereby move the thread carriers in their usual paths, the said attachment comprising a member connected to the driving element of the machine to receive motion therefrom, and means comprising a plurality of impositive connections positioned at a single control point for selectively connecting said member to the individual carrier bars each connection being coupled to a carrier bar for imparting impositively reciprocating motion thereto, the said impositive connections being such as to yield upon stoppage of a carrier bar while maintaining the driving connection potentially operative.
2. In a knitting machine having a driving ele- 150

ment, and a plurality of thread carriers and carrier bars, an attachment for reciprocating the said bars to thereby move the thread carriers in their usual paths, the said attachment comprising a single member connected to the driving element of the machine to receive an oscillatory motion therefrom, and means comprising a plurality of impositive connections positioned at a single control point for selectively connecting 5 said member to the individual carrier bars each connection being coupled to a carrier bar for imparting impositively reciprocating motion thereto, the said impositive connections being such as to yield upon stoppage of a carrier bar while 10 maintaining the driving connection potentially operative.

3. In a knitting machine having a driving element and a plurality of thread carriers and carrier bars, an attachment for reciprocating the 20 said bars to thereby move the thread carriers in their usual paths, the said attachment comprising a member connected to the driving element of the machine to receive an oscillatory motion therefrom, and means comprising a plurality of 25 impositive connections for selectively connecting said member to the individual carrier bars each connection being coupled to a carrier bar for impositively imparting reciprocating motion thereto, the said impositive connections being such as to yield upon stoppage of a carrier bar while 30 maintaining the driving connection potentially operative, said member and means being positioned at a single control point.

4. In a knitting machine having a driving element and a plurality of thread carriers and carrier bars, an attachment for reciprocating the said bars to thereby move the thread carriers in their usual paths, the said attachment comprising a member arranged transversely of said carrier bars and connected to the driving element of the machine to receive an oscillatory motion therefrom, a plurality of friction units, each of said units being secured in driving relation to an individual carrier bar, and means for effecting 45 driving engagement and disengagement between the individual friction units and said member.

5. In a knitting machine having a driving element and a plurality of thread carriers and carrier bars, an attachment for reciprocating the 50 said bars to thereby move the thread carriers in their usual paths, the said attachment comprising a member having a plurality of annular surfaces and arranged transversely of said carrier bars and connected to the driving element of the machine to receive an oscillatory motion therefrom, a plurality of friction bands, each of said bands encircling one of said annular surfaces and being secured in driving relation to an individual carrier bar, and means mounted on 55 each of said friction bands for releasably effecting frictional engagement between the band and the annular surface.

6. In a knitting machine having a driving element and a plurality of thread carriers and carrier bars, an attachment for reciprocating the 60 said bars to thereby move the thread carriers in their usual paths, the said attachment comprising a member connected to the driving element of the machine to receive oscillatory motion therefrom, means positioned at a single control point for selectively connecting said member to the individual carrier bars for imparting impositively reciprocating motion thereto, and means for altering the driving relation between 65

said driving element and said member for varying the amplitude of oscillation of said member.

7. In a knitting machine having a driving element, a thread carrier and a carrier bar, an attachment for reciprocating the said bar to thereby move the thread carrier in its usual path, the said attachment comprising a member connected to the said driving element of the machine to receive oscillatory motion therefrom, a friction band encircling said member and being secured in driving relation to the said carrier bar, and adjustable means for releasably contracting said friction band about said member and causing said band to frictionally grip said member.

8. In a knitting machine having a driving element, a thread carrier and a carrier bar, an attachment for reciprocating the said bar to thereby move the thread carrier in its usual path, the said attachment comprising a member connected to the said driving element of the machine to receive oscillatory motion therefrom and having an external annular surface, a split friction band encircling said annular surface, means for securing said band and the carrier bar in driving relation, and means for effecting driving engagement and disengagement between said friction band and said annular surface, said last-named means comprising an upstanding lug at each of the adjacent ends of said band, a cam lever, and a strap extending around one of said lugs and pivotally supporting said lever for engagement with the outer face of the other lug.

9. In a knitting machine having a driving element and a plurality of thread carriers and carrier bars, an attachment for reciprocating the 110 said bars to thereby move the thread carriers in their usual paths, the said attachment comprising a drum having an axial extension, a shaft extending through said drum and secured thereto, said shaft being connected to the driving 115 element of the machine to receive oscillatory motion therefrom, a fixed bearing at each end of said drum, one of said bearings receiving said drum extension, the other of said bearings receiving said shaft, a plurality of friction bands 120 encircling said drum, each of said bands being secured in driving relation to an individual carrier bar, and means for effecting driving engagement and disengagement between said friction bands and said drum.

10. In a knitting machine having a driving element and a plurality of thread carriers and carrier bars, an attachment for reciprocating the 125 said bars to thereby move the thread carriers in their usual paths, the said attachment comprising a drum connected to the driving element of the machine to receive oscillatory motion therefrom, said drum having a plurality of annular channels, a friction band located in each of said channels and secured to an individual carrier bar 130 in driving relation, and means for effecting driving engagement and disengagement between said friction bands and said drum.

11. In a knitting machine having a driving element and a plurality of thread carriers and carrier bars, an attachment for reciprocating the 140 said bars to thereby move the thread carriers in their usual paths, the said attachment comprising an oscillatable member, a plurality of friction units, each of said friction members being 145 secured in driving relation to an individual carrier bar, means for effecting driving engagement and disengagement between said friction units and said member, a crank arm connected to said oscillatable member, and a driving link connect-

ing said driving element to said crank arm, said driving link being adjustable along the length of said crank arm.

12. In a knitting machine having a driving element and a plurality of thread carriers and carrier bars, the combination of a single device comprising a plurality of friction units, each friction unit being adapted to transmit the drive from

10

bar, and thereby impart reciprocating motion to the bar, each friction unit becoming inoperative by stoppage of its carrier bar while said driving element continues in its normal movement and means for individually controlling said friction units, said device and means being positioned and controllable at a single control point. 80
